UNITED STATES PATENT OFFICE.

ARCHIBALD HYDE EHLE, OF PHILADELPHIA, PENNSYLVANIA.

MOTOR-DRIVEN TRUCK.

No. 849,838.

Specification of Letters Patent.

Patented April 9, 1907.

Application filed October 16, 1906. Serial No. 339,187.

To all whom it may concern:

Be it known that I, ARCHIBALD HYDE EHLE, a citizen of the United States, residing in Philadelphia, Pennsylvania, have invented certain Improvements in Motor-Driven Trucks, of which the following is a specification.

My invention relates to that class of trucks in which the driving mechanism, including the motor, is carried by the truck.

My invention is particularly adapted for use in connection with internal-combustion engines, such as gas-engines.

The object of my invention is to so construct the truck that it will properly support the entire driving mechanism without undue crowding, making the engine sufficiently large to properly propel the car, and yet not increase the rigid wheel-base beyond the ordinary length, so that the car will readily pass around the standard curves.

My invention also relates, further, to details of construction which will be fully described hereafter, reference being had to the accompanying drawings, in which—

Figure 1 is a plan view of my improved truck. Fig. 2 is a side view, partly in section, on the line 2 2, Fig. 1. Fig. 3 is a longitudinal sectional view on the line 3 3, Fig. 1, showing the car in dotted lines. Fig. 4 is an end view looking in the direction of the arrow 4, Fig. 3. Fig. 5 is a transverse sectional view on the line 5 5, Fig. 1. Fig. 6 is a transverse sectional view on the line 6 6, Fig. 1. Fig. 7 is an enlarged sectional plan view on the line 7 7, Fig. 9, of the change-gear. Fig. 8 is an enlarged plan view showing the shifting mechanism for the change-gearing. Fig. 9 is a sectional view on the line 9 9, Fig. 8, and Fig. 10 is a side view of a car mounted on my improved truck.

A is the frame of the truck, having pedestals *a*, in which are mounted the boxes *a'* for the axles B B'. On these axles are the wheels *b* *b'*, respectively. The axle B is the driving-axle, which is geared to the motor in the manner fully described hereafter. In some instances, however, the axle B' may also be driven by a chain or other connection from the main axle B.

A' is a cross-frame carrying the center bearing-plate *a'*, on which the car-body is

pivoted, as clearly shown by dotted lines in Fig. 3.

It will be understood that my invention is particularly adapted for driving an individual car, using my improved motor-driven truck in place of the ordinary forward truck of the car; but it will be further understood that the invention can be used simply as a locomotive, to which a train of cars can be coupled.

D D are two longitudinal beams extending the full length of the frame A and bent in the manner clearly illustrated in Fig. 2. These two beams D D support the engine E, which in the present instance is a four-cylinder gasoline-gas engine, the four cylinders being indicated by *e*, and the crank-shaft is contained in the casing *e'*. The crank-shaft *E'* projects at each end of the casing and is coupled to the transmitting mechanism in the manner hereinafter described.

The engine can be of any ordinary type of gas or gasoline engine; but I preferably use gasoline or alcohol. I have simply shown the valves and other mechanism of the gas-engine in outline, as they form no part of the present invention. I so design the truck that a very large gas-engine can be mounted between the two axles, the transmitting mechanism being carried by a trailing truck F. This enables me to use all the available space between the main axles for the accommodation of an engine of a sufficient size to properly propel the car. In the present instance the cross-frame A', carrying the center bearing-plate, extends over the engine E, so that, as shown in the drawings, the engine is mounted between the two axles and below the cross-frame. While an ordinary size of engine will readily drive a car after it is set in motion, it is very difficult, especially on upgrades, to start a car with a gas-engine. Therefore a very large gas-engine has to be used in order to make it available for car service.

G is a dynamo, the armature-shaft *g* of which forms a continuation of the shaft *E'*. This dynamo is mounted on the frames D D, as clearly illustrated in Fig. 1. The shaft *g* is shaped at the end to receive a crank, so that the shaft and the engine-shaft can be turned when it is desired to start the engine.

In some instances the generator may be used as a motor to turn the crank-shaft of the engine if the electricity is stored in a storage battery. By providing the dynamo G, as indicated, the lighting and heating of the car can be accomplished without the use of a separate engine.

In order that the forward axle B' can be readily removed from the frame, I make a short connecting-shaft e^2 , which is coupled to the engine-shaft E' and to the dynamo-shaft g, as clearly indicated in Figs. 1 and 3. By removing this section e^2 the axle B' can be dropped from the frame and readily removed from the truck. The section e^2 is coupled to the shaft g by a gimbal-joint g' of any ordinary type, so that it is not necessary to have the dynamo absolutely in line at all times.

H is a speed-box.

I is a clutch of the magnetic type, in the present instance mounted between the shaft H' of the speed-box and the engine-shaft E'. A short shaft I' of the magnetic clutch is coupled to the engine-shaft E' by a short section e^3 directly under the shaft B, so that on removing this section the shaft B can be detached from the frame in a similar manner to the shaft B' previously described. The joint e^4 is a gimbal-joint, as there may be a slight variation in the alinement between the two shafts E' and I'. The shaft I' of the magnetic clutch is connected to the shaft H' by a gimbal-joint i for the same purpose as the joint e^4 . It will be seen that throughout the length of the truck the shaft is divided into sections, the several sections being united by gimbal-joints, so that each part can have a slight independent movement without binding upon the bearings or without producing undue friction.

I have shown simply one form of magnetic clutch—that is, the disk type—but it will be understood that any form of clutch may be used whether it is a magnetic or mechanical clutch. I prefer to use the magnetic clutch electrically operated, as the wires can be readily run from the clutch-case to the cab of the car. By using the clutch the engine-shaft can be readily disconnected from the transmission-gear.

The transmission-gearing illustrated in the drawings is fully described and claimed in detail in a companion application filed even date herewith. Therefore I will not describe it minutely in this specification.

m is the first intermediate shaft, and n is the second intermediate shaft. Loose on the shaft m are gears m' , which mesh with a pinion h on the shaft H'. A clutch m^2 , mounted on the squared portion of the shaft m, is arranged to be shifted by the shifting-spindle h^2 , having a forked arm engaging the clutch-sleeve, so that the clutch may be thrown either to the right or left to reverse the move-

ment of the shaft m or remain in the central position clear of the gear-wheels when it is desired to disconnect the engine.

Keyed to the shaft m are two gear-wheels p p', the wheel p' being less in diameter than the wheel p, and these wheels gear, respectively, with wheels q q' loose on the shaft n. A clutch-sleeve n' is arranged to slide on the squared portion of the shaft to engage either one of the wheels q q', and this clutch-sleeve is shifted by means of the spindle h^3 , having a forked end, as indicated in Fig. 9, so that when the clutch-sleeve n' is in gear with the wheel q the car will be driven at high speed, and if the sleeve n' is clutched to the gear-wheel q' the car will be driven at low speed. The shaft n extends beyond the frame H² of the speed-box H at each side in the present instance and is tapered to fit the tapered opening in the sprocket-wheels N N, which are keyed to the shaft, as indicated in Fig. 7. On the axle B are two sprocket-wheels B², and drive-chains N' pass around the sprocket-wheels N and B², so that the power is transmitted to the axles B by the flexible chain-gearing.

The spindles h^2 and h^3 are held in their central position by springs h^4 , Figs. 1 and 8. These springs are connected to the levers h^5 , and the levers are connected to the rods k of hydraulic cylinders k', the valve mechanism of which is controlled by electric mechanism similar to that described in my application for patent filed September 12, 1905, under Serial No. 278,127. The wires lead from this controlling mechanism to a point on the car within easy access of the driver, so that the driving mechanism is controlled entirely through the medium of the electric mechanism.

There is preferably no connection between the car and the truck with the exception of the pivot-pin of the truck and the wire leading from the controller on the car-body to the mechanism on the truck. The position of the truck in respect to the car is clearly indicated in the side view, Fig. 10, which illustrates one form of car onto which my improved truck can be mounted. The speed-box and transmission-gear, it will be noted, are beyond the main frame of the truck, and in order to properly support these I mount a swing-truck F at the rear of the main truck and pivot the swing-truck at f to an extension of the base-frame H², as clearly illustrated in Figs. 1, 3, and 9. The truck F is framed to support the boxes s of the shaft S, on which are mounted the wheels s', and extending from the frame of the truck is a curved radius member F', which travels in a suitable support on the forward portion of the speed-box frame H². The frame f', to which the extension of the speed-box frame H² is pivoted, is connected by links f² to the

main frame f^3 , carrying the boxes, so that the axle is free to swing independently of the main truck and will take the curves independently of the main truck, so that while the swing-truck F supports the rear end of the speed-box it does not interfere with the proper working of the main truck.

By the construction above described I am enabled to mount the axles B B' in a manner similar to the axles of an ordinary truck, and I can utilize an equalizing-beam u , which rests upon the boxes a' of the axles B B' and mount equalizing-springs u' between the beam and the under side of the upper frame of the truck, as clearly illustrated in Figs. 2 and 10. This will relieve the engine and other parts of the mechanism from severe shocks and make the truck ride more evenly than if the axles were mounted in rigid boxes on the truck-frame.

I claim—

1. The combination of a truck-frame, two axles, bearings in the said frame for the axles, an engine mounted on the frame between the two axles, an extension at one end of the frame, and transmission-gear mounted on said extension, a longitudinal main shaft connected to the engine-shaft and to the transmission-gear, and means connecting one of the axles of the truck with the transmission-gear, substantially as described.

2. The combination of a truck-frame, two axles, wheels on said axles, the axles being mounted in bearings on the truck-frame, a trailer-truck connected to the truck-frame, an engine mounted between the axles of the main frame, and transmission-gear connected to the shaft of the engine and mounted on an extension of the truck-frame, the rear of said extension being supported by the trailer-truck, substantially as described.

3. The combination of a main truck, two axles mounted on said truck, an engine mounted on the truck between the axles having a longitudinal crank-shaft, an extension of the main truck, a swing-truck pivoted to said extension, transmission-gearing mounted on said extension and driven by the engine-shaft, and driving mechanism connecting the speed-box with the rear axle of the main truck, substantially as described.

4. The combination of a main truck, two axles mounted thereon, a longitudinally-arranged gas-engine mounted on the truck between the two axles, said truck having an extension, a swing-truck pivoted to said extension, a speed-box mounted on the extension and coupled to the engine-shaft, two transverse intermediate shafts in the speed-box, the second intermediate shaft having sprocket-wheels at each end, sprocket-wheels on the rear axle of the main truck, and chains passing from the sprocket-wheels of the second intermediate shaft to the

sprocket-wheels on the axle, substantially as described.

5. The combination of a main truck-frame, two axles mounted thereon, a longitudinally-arranged gas-engine mounted on the frame between the axles, a speed-box beyond one of the axles, the shaft of the speed-box being connected to the shaft of the engine, the driving-shaft being made in sections connected together by gimbal-joints, substantially as described.

6. The combination of a main truck-frame, two axles mounted in the frame, a longitudinally-arranged gas-engine mounted on the frame between the two axles, a driving-shaft extending under the rear axle, change-gearing connected to the said shaft, the said shaft being made in sections, one section being directly under the rear axle of the main truck so that on detaching this section the main axle can be removed from the truck-frame, substantially as described.

7. The combination of a truck-frame, two axles mounted therein, a gas-engine mounted on the frame between the two axles, a longitudinal shaft extending throughout the length of the truck and under both axles, said shaft having detachable sections directly under the two axles, so that both axles can be removed from the truck-frame on detaching the sections, substantially as described.

8. The combination of a truck-frame, two axles mounted thereon, a longitudinally-arranged gas-engine mounted between the two axles, a longitudinal shaft extending throughout the length of the truck, a dynamo mounted on one end of the truck, the shaft of the dynamo forming a continuation of the shaft of the gas-engine, substantially as described.

9. The combination of a truck, two axles mounted thereon, a gas-engine mounted on the truck between the two axles, a sectional longitudinal shaft extending rearwardly from the engine, a magnetic clutch arranged to couple two sections of the shaft together, speed-gearing driven by said shaft, and means connecting the speed-gearing with the driven axle, substantially as described.

10. The combination of a truck-frame, two axles arranged comparatively close together so as to provide a short wheel-base, a trailer-truck coupled to the main truck-frame, a gas-engine, and gearing mounted on the said main truck-frame for driving the same, substantially as described.

11. The combination of a main truck, two axles mounted thereon, equalizing-gear supporting the frame, a gas-engine longitudinally mounted on the frame between the two axles, a longitudinal shaft made in sections extending under the axles forming continuations of the engine-shaft, a dynamo mounted on the forward end of the truck, the dynamo-shaft forming a continuation of the en-

gine-shaft and connected thereto by a gimbal-joint, a clutch coupling the two sections of the shaft, a change-gear driven by the said shaft, a gimbal-joint between the speed-gear and the clutch and between the clutch and the engine, with means connecting the speed-gear with the driven axle of the truck, substantially as described.

In testimony whereof I have signed my name to this specification in the presence of two subscribing witnesses.

ARCHIBALD HYDE EHLE.
